Primary Examiner—Alan P. Douglas*Assistant Examiner*—Robin V. Taylor*Attorney, Agent, or Firm*—Myron B. Kapustij; Malcolm L. Sutherland[57] **CLAIM**

The ornamental design for a showerhead, as shown and described.

DESCRIPTION

FIG. 1 is a front perspective view of a showerhead showing our new design;

FIG. 2 is a side elevational view thereof, the other side being a mirror image;

FIG. 3 is a front elevational view thereof; and,

FIG. 4 is a rear elevational view thereof.

The broken line representation of the attachment member at the rear of the showerhead in FIGS. 1,2 and 4 is for purposes of illustration and forms no part of the FIGS. 1,2 and 4.
